APPLICATOR

Wilma O. Heaton, Oakland, Calif.

Application March 8, 1934, Serial No. 714,550

8 Claims. (Cl. 132—1)

The invention relates to an applicator of the nature of a finger stall, and further relates to a package including the applicator.

An object of the invention is to provide an applicator which is adapted for mounting on a person's finger for use in the application of a cosmetic substance to the face whereby to keep the finger clean of the applied substance and at the same time protect the face from infection from the finger.

Another object is to provide an applicator which is particularly adapted to accomplish the aforesaid and other desirable objects.

A further object is to provide a compact package including the applicator and wherein the applicator retains its normal shape and may be fully protected when not in use.

The invention possesses other objects and features of advantage, some of which, with the foregoing, will be set forth or be apparent in the following description of a preferred embodiment of the invention which is illustrated in the accompanying drawing, in which,

Figure 1 illustrates the use of an applicator embodying the invention for smoothing an application of lip rouge in place on a person's lips.

Figure 2 is an enlarged longitudinal section of the applicator as mounted on a person's finger.

Figure 3 is an elevation of a protective cap for receiving the applicator.

Figure 4 is an elevation of the applicator.

Figure 5 shows a closure cap for the applicator cavity, said cap carrying a stick of lip rouge.

Figure 6 is an axial section taken through a package comprising an assembly of the various elements shown in Figures 3 to 5 inclusive.

Figure 7 is a section at the broken line 7—7 in Figure 4.

Figure 8 is a section at 8—8 in Figure 6.

In its present embodiment, the invention is disclosed in an applicator 11 which is particularly designed for applying and/or smoothing a deposit of rouge on a person's lips, such a deposit having been derived from a rouge stick 12 which extends from a usual casing 13, or from some other source of the rouge. Essentially, the applicator 11 comprises a finger cot 14 formed of soft rubber or the like and mounted on and extending axially from a ring member 15 in unitary association therewith.

Preferably, and as shown, the cot 14 is closed at its tip end, is tapered toward said end, and is of generally elliptical cross-section throughout its length for conformity with the generally elliptical cross-section of the outer portion of a person's

finger. At its open inner end the cot 14 is formed with a solely inturned bead 18 for engagement in a complementary groove 17 of the ring 15 for mounting the cot on the ring, said ring having a similar cross-section to that of the cot at its base.

Since for properly smoothing and distributing rouge in place, the sense of touch must be used as well as the sense of sight, it is a common practice to use the highly sensitive finger tips for finishing an application of a rouge material to a skin surface. Accordingly, at least the tip portion of the applicator cot 14 is preferably made as thin and close-fitting to a finger therein as is possible with the material used for the cot whereby the sense of touch at a finger tip in the cot may be used to a maximum amount as the applicator portion thereof is used.

It is further desirable that an applicator cot of the character described shall retain its cup-like form when not in use, and it is therefore preferred that the side walls of the cot shall be so constituted that its normally elliptic cross-section will be maintained. In the present instance, the latter purpose is accomplished in a cot of homogeneous structure by forming the same to have side walls of requisite thickness to provide the needed stiffness of structure. Accordingly, and as is brought out in Figures 2 and 6 and 7, the cot side wall is somewhat thicker than, and tapers into, the thin end wall portion through which the user must be able to feel the rouge and the surface to which it is applied.

The present applicator cot structure is particularly designed to be made of a soft vulcanized and stretchable rubber composition, and the tapered form of the cot is arranged to provide for the stretched engagement of at least the working tip portion over a person's finger whereby a skin-tight fit may be afforded at the end cot portion which is to be applied to the rouge. It will be understood, however, that other materials having the specified qualities might be used for the cot instead of rubber. Furthermore, at least those outer surface portions of the applicator which are to be applied to the rouge would preferably be roughened slightly rather than smooth. The material of the cot would be generally impervious.

Preferably, though not necessarily, the ring 15 is arranged to closely fit the finger portion thereof when the cot 14 is mounted in operative position and condition on a finger. As particularly shown, the ring 15 is shaped as from a piece of tubing formed of relatively inflexible sheet material of a uniform gauge, and the groove 17 is provided

in a circumferentially depressed ring portion at the extreme outer ring edge. The annular ridge 18 thus provided at the outer end of the ring bore may more or less closely engage a person's finger 5 for frictionally holding the ring in place when the cot is fully stretched over the finger end. While the cot is of itself of a non-collapsing structure, it will be understood that the ring 15 assists in maintaining it in its normal shape.

10 The inner cot edge portion at the bead 16 is arranged for stretching into its place in the groove 17 whereby the bead is operative to releasably fix the cot to the ring in unitary association therewith, it being noted that solely the ring need be 15 engaged by a person's fingers while mounting or dismounting the cot with respect to a finger; in this manner, the exterior of the cot need not be touched by a person's hand. The cot would normally remain in mounted disposition on the ring 20 whereby the cot and ring constitute an applicator unit; removal of the cot from the ring would generally be effected only for a cleaning or replacement thereof.

A protective enclosure is provided for the cot 25 when the applicator unit is not in use, the enclosure elements utilizing the ring 15 as a mounting means therefor. As particularly shown, caps 21 and 22 are provided for mounting at the outer and inner ends respectively of the ring, 30 the cap 21 being shaped to receive the non-collapsing cot 14 therein without any contact with it, and the cap 22 being arranged to extend across the inner ring end to close the space 23 jointly provided within the cot and ring. The cross-section 35 of the two caps are each similar to that of the ring 15 whereby the space occupied by the assembly of the caps with the ring may be a minimum. It will be noted that the applicator may be placed on or removed from a finger while the 40 cap 21 is mounted in place on the ring 15.

As particularly illustrated, the ring 14 is intermediately formed to have an encircling flange 24 thereabout for providing a stop to limit the degree of engagement of the caps 21 and 22 on the 45 ring. The caps are formed of stiff sheet material and are arranged to frictionally embrace the ring at opposite sides of the stop flange 24, it being noted that the outer face of the base portion of the cot 14 preferably lies within the outer surface of the ring portion which is engaged in the 50 base of the cap 21 whereby it may not be injuriously contacted by the cap as the latter is mounted on, or is dismounted from, the ring.

The space 23 which is jointly defined by and 55 within the cot 14 and ring 15 may be utilized as a container, its use as a storage place for the rouge stick 12 being particularly indicated in Figure 6. The casing 13 for the rouge stick is provided with an encircling bead 26 near its open end, such a 60 bead being usual when a cap (not shown) is to be applied for completing the encasing of the stick of rouge. In the present instance, however, a clip assembly 27 is provided within the cap 22 for receiving and gripping the portion of the casing 13 65 beyond the bead 26 and nearest to the exposed rouge stick portion, whereby the stick of rouge may be releasably held and supported within the space 23 and without contact with the interior of the cot 14 or the cap 22. As shown, the clip assembly 27 comprises a set of spring clips extending from a plate 29 which is suitably fixed to and 70 against the inner end of the cap 22.

The described combination of the applicator unit 11 with the caps 21 and 22 and the rouge stick 12 is understood to provide a package which 75

may be produced and sold as a unitary article of manufacture. As indicated in Figure 1, the applicator may be mounted on a finger of a hand which holds the rouge stick for the application thereof; in this manner, the applicator and stick 5 may be alternatively applied as required with only one hand in use for the purpose.

While for hygienic reasons it is generally preferable that the cot 14 have a closed outer end for completely enclosing the finger tip and its 10 nail, it will be understood that a fingernail opening might be provided in the cot end for permitting the protrusion of a long finger nail there-through and from the cot. The latter arrangement would, of course, prevent the reversible 15 mounting and use of the applicator cot which is hereinbefore particularly shown and described.

From the foregoing description taken in connection with the accompanying drawing, the advantages of the construction and method of use 20 will be readily understood by those skilled in the art to which the present invention appertains. While I have described the features and the principles of operation of a device which I now consider to be a preferred embodiment of my invention, 25 I desire to have it understood that the specific showing is primarily illustrative, and that such changes may be made, when desired, as fall within the scope of the following claims.

I claim:

1. A rouge applicator comprising a finger cot 30 of flexible and elastic material for mounting in stretched condition on the outer end portion of a person's finger; the cot wall being imperforate and smooth and relatively thin at its rounded end portion whereby the sense of touch of a finger tip therein is arranged to be operative therethrough with a minimized degree of interference therewith.

2. A rouge applicator comprising a finger cot 40 of soft vulcanized rubber or the like for mounting in stretched condition on a person's finger, the cot wall having smooth surfaces and being so thin at its rounded end portion that conditions at a rouge-receiving surface engaged therewith are arranged to be readily felt therethrough by a finger 45 therein.

3. An applicator for use in depositing and/or spreading and/or smoothing material at a surface and comprising a finger cot of flexible and elastic 50 material for mounting in stretched condition on the end portion of a person's finger, the rounded end portion of the cot being imperforate and as thin as possible whereby conditions at said surface when touched therewith may be readily felt 55 therethrough by a finger therein, and the remaining cot wall portions being relatively thick whereby the cot is arranged to retain the general shape of a finger end when dismounted.

4. An applicator of the class described comprising a cot of flexible and elastic material for mounting on a finger and adapted for the direct application of an imperforate tip portion thereof to a surface for depositing and/or spreading and/or smoothing material on the surface, and a 60 finger ring of relatively inflexible and inelastic material fixed to said cot at the inner end thereof in coaxial relation therewith, said cot and ring having mutually similar elliptic cross-sections 65 therelong.

5. A new article of manufacture comprising an applicator cot of flexible material for mounting on a person's finger and adapted for the direct application of an outer end portion thereof to a surface for depositing and/or spreading and/or 70 75

smoothing material thereat, a finger ring of relatively inflexible material fixed to said cot at the inner end thereof in coaxial relation thereto, and a closed cap of relatively inflexible material removably mounted on the outer end of said ring and enclosing the cot without contact therewith and as a protective means therefor.

6. A new article of manufacture comprising an applicator cot of flexible material for mounting 10 on a person's finger and adapted for the direct application of an outer end portion thereof to a surface for depositing and/or spreading and/or smoothing material thereat, a finger ring of relatively inflexible material fixed to said cot at the inner end thereof in coaxial relation therewith, a closed cap of relatively inflexible material removably mounted on the outer end portion of said ring and enclosing the cot without contact therewith and as a protective means for the cot exterior, and a closed cap of relatively inflexible material removably mounted on the inner end of said ring for cooperation with the ring as a protective means for the cot interior.

7. A new article of manufacture comprising an

applicator finger cot of flexible material and non-collapsing structure, a finger ring of relatively inflexible material carrying said cot at its outer end, a closed cap of relatively inflexible material removably mounted on the inner end of said ring and cooperative with the cot and ring to define a closed receptacle space within the cot and ring, and means on said cap to mount an article thereon whereby said article may be disposed in said space in fixed spaced relation to the cot and ring 10 when the cap is mounted on the ring.

8. A new article of manufacture comprising an applicator cot of flexible material for mounting on a person's finger and adapted for the direct application of an outer end portion thereof to a 15 surface for depositing and/or spreading and/or smoothing material thereat, a finger ring of relatively inflexible material fixed to said cot at the inner end thereof, and a closed cap of relatively inflexible material removably mounted on the inner end of said ring for cooperation with the ring as a protective means for the cot interior.
